UNITED STATES PATENT OFFICE.

WILLIAM MALOTT, OF TORONTO, ONTARIO, CANADA.

WEATHER-STRIP FOR DOORS.

No. 896,310.

Specification of Letters Patent.

Patented Aug. 18, 1908.

Application filed April 25, 1907; Serial No. 370,245.

To all whom it may concern:

Be it known that I, WILLIAM MALOTT, of the city of Toronto, in the county of York, in the Province of Ontario, Canada, have invented certain new and useful Improvements in Weather-Strips for Doors, of which the following is the specification.

My invention relates to improvements in weather strips for doors, and the object of 10 the invention is to devise an extremely simple strip applicable to the bottom of a door, which will effectually exclude the draft when the door is closed, and which when the door is being closed will automatically close the 15 crevice at the bottom of the door and yet will rise immediately the door is released in opening.

A further object is to make a weather strip applicable to the bottom of the door, 20 which is not liable to get out of order or wear out and in which there will be practically no friction in throwing the strip into position to exclude the draft.

My invention consists essentially of a strip 25 of spring metal preferably brass extending longitudinally underneath the bottom of the door, a strip preferably of galvanized iron or zinc into which one edge of the aforesaid strip fits, the said galvanized strip being 30 curled or formed up to receive the longitudinal pivotal rod, end plates forming a journal for the ends of the rod, a counter-balancing bar extending longitudinally to one side of the pivotal rod, and an arm connected 35 to the bar and extending through an arc-shaped slot on one of the end plates and a bracket on the frame of the door jamb with which the end of the arm is designed to contact to throw the strip down to close the 40 crevice, the parts being otherwise arranged and constructed as hereinafter more particularly explained.

Figure 1, is a perspective view of the bottom of a door showing my invention applied thereto and the door nearly closed. Fig. 2, is a similar view showing the door ajar. Fig. 3, is an enlarged cross sectional detail.

In the drawings like letters of reference indicate corresponding parts in each figure.

50 A is the door and B B' the jambs thereof. C is a bracket secured to the jamb B' near the bottom of the face adjacent to the edge of the door.

D and D' are end plates secured to the 55 edges of the door at the bottom.

E is a strip made preferably of brass and F

is a strip made preferably of zinc or galvanized iron having a fold F' into which one edge of the strip E fits. The strip F is also provided with a curled forward end F² 60 through which extends a rod G, which is journaled at the end in the end plates D' or the rod may be held stationary in the end plates, and the curled end F' of the strip F may be journaled thereon as may be found 65 best.

H is a counter-balancing bar, which is secured by rivets H' on the upper side of the strip F, the rivets extending through the strips E and F.

D² is a supplemental bearing secured within the recess D and in which the center portion of the rod G is journaled.

J is a bell-crank-shape arm secured at the lower end in the end of the bar H and having the upper bent end extending through an arc-shaped slot D³ in the end plate D.

I is a groove in the bottom of the door, which is so shaped as to permit the tilting of the strip E, so that the outer edge may be 80 forced down against the sill of the door.

E' is a strip of felt, which I preferably place near the outer edge of the strip E in order to make the contact with the sill as close as possible and prevent any openings underneath the edge of the strip. The strip E being a spring-strip may be forced down and will bend, and thereby from end to end insure the crevice being closed no matter whether there is unevenness in the sill or not. 90

When the door is being closed the projecting end of the bell-crank-shape arm J contacts with the bracket C and forces down the outer edge of the strip E against the sill so that when the door is closed such edge is held 95 tightly against the sill and will effectually exclude draft from passing under the crevice of the door.

It will be seen that immediately the door is open the slightest, the weight of the bar H 100 will immediately cause the edge of the strip E to rise and thus allow the door to be readily opened without any liability of the strip coming in contact with the floor or sill. It will also be noticed that when the curled edge F² 105 rises it hugs the groove when the strip is depressed, and thereby prevents a draft passing upwardly and around through the groove.

What I claim as my invention is:

1. In a weather strip for the bottom of 110 doors, the combination with the door having a longitudinal groove in the bottom thereof,

of the longitudinal strip comprising a spring strip and the folded strip into which one end of the spring strip fits provided with a curled edge, the rod extending through the curled edge, journals in the end plates for the rod and means on the rod operated from the door jamb for throwing the flexible strip against the sill and at the same time causing the curled edge to press in the groove at the bottom of the door as specified.

2. In a weather strip for the bottom of doors, the combination with the longitudinal strip comprising a spring strip and a folded

strip into which one edge of the spring strip fits provided with a curled edge, the end 15 plates, the rod extending through the curled edge and into journals in the end plates and means on the end of the strip designed to come in contact with the projection on the jamb for tilting the strip as and for the purpose specified.

WILLIAM MALOTT.
